(Cl. D34—5)

FIG. 1.

FIG. 2.

FIG. 3.

FIG. 4.

FIG. 5.

FIG. 1 is a perspective view of the individual pieces of a set of nesting chessmen showing my new design;

FIG. 2 is a perspective view of a pawn looking upwardly from below the bottom;

FIG. 3 is a top plan view of a pawn;

FIG. 4 is an elevational view of a pawn; and

FIG. 5 is a bottom plan view of a pawn.

The ornamentation on the reverse side of each piece not visible in FIG. 1, is a mirror image of the ornamentation illustrated on the visible side.

I claim:

The ornamental design for a set of nesting chessmen, as shown and described.
